TO THE WHITNEY MANUFACTURING COMPANY, OF HARTFORD, CONNECTICUT, A COR-
PORATION.

DRIVE-CHAIN.

No. 893,779.

Specification of Letters Patent.

Patented July 21, 1908.

Application filed January 15, 1908. Serial No. 411,007.

To all whom it may concern:

Be it known that we, WILLIAM M. BUTLER and WARREN J. BELCHER, citizens of the United States of America, residing at Hartford, in the county of Hartford and State of Connecticut, have invented new and useful Improvements in Drive-Chains, of which the following is a specification.

This invention relates to frictional drive-chains, the object of the invention being to provide a driving-chain of this character embodying frictional contact surfaces inclined one to the other to bear wedge-like in a V-shaped groove of a driving-pulley, the frictional element of the construction consisting of some suitable substance, as leather or the like, completely encircling the chain and being secured in separate segment-shaped pieces to the links of the chain by means of fastening devices integral with said links, these pieces of frictional material providing, when the chain is running substantially in a straight line, a continuous smooth upper or outer surface of said frictional material.

In the drawings forming part of this application,—Figure 1 is a side elevation of a number of connected links of a drive-chain showing the preferred embodiment of the invention. Fig. 2 is a sectional elevation on line 2—2, Fig. 1, the plane of the section being through two of the side links of the chain, the portion of the grooved guiding pulley being shown in dotted lines. Fig. 3 is a perspective view, on a somewhat enlarged scale, of a portion of a chain showing the construction and arrangement of the links and blocks, and showing also a portion of the frictional material encircling the same. Fig. 4 is a plan view of one of the pieces of frictional material, the scale of this view being the same as Fig. 1. Figs. 5, 6, 7, and 8 illustrate the method of applying the encircling strips of frictional material whereby they may be secured to the chain under such tension as is necessary to hold them securely thereon.

Referring now to these drawings, the chain is made up of alternate blocks *a* and side-plates or links *b* the latter being riveted to the blocks in the usual manner, but unlike the usual construction the side plates *b* are extended beyond the lower or inner edge of the blocks, as indicated by *b'*, these extensions being inclined one towards the other, as shown in Figs. 2 and 3 clearly, the angle of

inclination being the same as that of the sides of the groove of the driving pulley *c* against which they bear, as indicated in dotted lines in Fig. 2. The lower edges of these extensions *b'* of the side plates *b* are provided with teeth *d* adapted to extend through the opposite edges of a piece of flexible frictional material *e* of a shape shown in Fig. 4, substantially, which completely encircles the chain inclosing the two oppositely located side plates, as shown in Fig. 3, and portions of the contiguous ends of the blocks *a* located between said side plates. To facilitate the application of this flexible material *e* to the side plates or links *b*, as described, the teeth *d* at the lower edge of the plates are first preferably bent outwardly, as shown in Figs. 3, 5, and 6, the opposite edges of the flexible material *e* being perforated to receive these teeth before the strip is applied to the chain.

The various steps usually followed in applying the frictional material are illustrated in succession in Figs. 5, 6, 7, and 8 and in applying the material in this manner it may be stretched more or less when the teeth *d* are bent toward each other from the position shown in Figs. 5 and 6 to the positions shown in Figs. 7 and 8. This process is facilitated if the encircling strips of frictional material are first softened in any well known manner.

When the teeth *d* have been bent around to the position shown in Figs. 7 and 8, the points thereof may be, by any suitable tool, turned over, as shown in Fig. 8, to clench them against the surface of the flexible material, and these retaining teeth, located as they are on the under side of the chain, never come in contact with any surface on the grooved driving pulley *c*.

An important feature of this invention lies in the fact that by means of this construction the upper or outer surface of the chain is left entirely smooth and only the surface of the material *e* is exposed; this surface, therefore, constitutes one to which an idler pulley may be applied to take up any slack in the chain, and whereby said pulley will run quietly and without subjecting either itself or the surface of the chain to any wear. This is an important feature inasmuch as frictional drive-chains in nearly all cases require the application of an idler pulley to maintain them in effective frictional relation to the pulleys over which they run; and as chains of this character have heretofore been constructed, it has

been impossible to apply an idler pulley which would have an unbroken yielding surface to run on, as in chains of this character it has heretofore been the practice to secure the strips of frictional material by means of rivets extending through said material in the space between the side plates.

If desired, when a chain is to be subjected to severe conditions of service, one or more teeth *f* may be formed on the upper edge of the plates *b*, as shown in the various figures of the drawing, for the purpose of preventing any slip of the chain-inclosing piece of frictional material *e*; but these teeth or projections should be of such length that they will not extend through the material but serve only as points for the engagement of the inner surface thereof to prevent the material from slipping.

20 A chain made as described and shown herein results in a construction which not only is strong and useful and neat in appearance, but it is one which may be most cheaply manufactured as the side plates *b* and the 25 fastening devices for the encircling pieces of frictional material may be all made on a punch-press at one operation and the labor of putting the parts of the chain together and fitting the strips of material thereon in the 30 manner described is relatively small.

What we claim, is:—

1. A drive-chain consisting of blocks, and side-plates to pivotally unite said blocks, said side plates extending beyond the lower 35 edge of the blocks, a strip of pliable material to encircle each pair of side plates, there being teeth on the lower edges of the plates

to extend through the meeting edges of said strip, the ends of the teeth being bent over to secure the strip in position.

2. A drive-chain consisting of blocks, and side-plates to pivotally unite said blocks, said side plates extending beyond the lower edge of the blocks, and being inclined one towards the other, a strip of pliable material 45 to encircle each pair of side plates, there being teeth on the lower edges of the plates to extend through the meeting edges of said strip, the ends of the teeth being bent over to secure the strip in position.

3. A drive-chain consisting of blocks, and side-plates to pivotally unite said blocks, said side plates extending beyond the lower edge of the blocks, a strip of pliable material to encircle each pair of side plates, there being 55 teeth on one edge of the side plates to extend into said strip of material to prevent it from slipping, and means to secure together the meeting edges of said strip.

4. A drive-chain consisting of blocks, and side-plates to pivotally unite said blocks, said side plates extending beyond the lower edge of the blocks and being inclined one towards the other, a strip of pliable material to encircle each pair of side plates, there being 65 teeth on the upper and lower edges of the side plates to engage the strip, and secure it immovably to each pair of side plates.
